RETRACTABLE STEP

Norman J. Harvey, Bellevue, Nebr.

Application May 1, 1946, Serial No. 666,479

4 Claims. (Cl. 228—48)

1

This invention is a retractable utility step. Small children, when making use of a lavatory, usually require a step or support of some kind upon which to stand. An ordinary step, as generally employed is not particularly satisfactory for the purpose since such a step might be easily tipped, especially if not placed in exactly the right position. A child using such a step, may place it in the wrong position and, in attempting to reach the lavatory, may stand on the edge and thus tip the step over, possibly resulting in injury to himself.

It is, therefore, a primary object of my invention to provide a utility step which is self-positioning, retractable to an "out-of-the-way" position, and easily operated.

Another primary object of my invention is to provide a simple utility step of improved shape, and one which is particularly adapted for the use of children.

It is another object of my invention to provide such a simple utility step with mounting means adapted to secure the step in the position in which it is normally used and thus prevent its tipping over, or to support it in a raised, "out-of-the-way" position, against a wall, when it is not needed.

A still further object of my invention is the provision, in a device of this nature, of means for mounting a utility step in such a manner that it may be removed from its supporting mechanism and used elsewhere as a simple utility step.

Other and further features and objects of the invention will be more apparent to those skilled in the art upon a consideration of the accompanying drawings and following specifications, wherein are disclosed several exemplary embodiments of the invention, with the understanding, however, that such changes may be made therein as fall within the scope of the appended claims, without departing from the spirit of the invention.

In the drawings:

Figure 1 is a view in perspective illustrating a utility step, constructed in accordance with my invention, as it would appear when mounted beneath a lavatory.

Figure 2 is a longitudinal view, in section, of the utility step and its supporting mechanism as taken along the line 2—2 of Figure 1.

Figure 3 is a view, in section, of the step as taken along the line 3—3 of Figure 2.

Figure 4 is a vertical section taken along the line 4—4 of the wall bracket shown in Figure 5.

Figure 5 is a top view of the bracket shown in

2

Figure 4, with the cover removed to better show the mechanism, and

Figure 6 is a view in perspective of a modified form of my wall mounting-bracket.

Referring now to these drawings, and particularly to Figure 1 thereof:

The utility step which I have indicated generally at 10, is hingedly connected, by means of a pair of arms 11 and 12, to the wall brackets indicated generally by the numerals 13 and 14, and these members are securely mounted, by means of wood screws or the like, on the baseboard 15 beneath the lavatory 16. The normal position of the stool is that shown by solid lines in Figure 1, the position being the one best suited for the use of small children making use of the lavatory. The stool, when not actually in use, may be tilted upwardly and rearwardly to an out-of-the-way position beneath the lavatory as indicated at 10a by dashed lines.

The utility stool 10 includes the panel-like end members or legs 17. These end panels are secured together in spaced relation by means of the top panel 18 and the narrow side walls 19 and 20, which members are flanged, as at 21, to permit their being secured to the end panels by spot welding or the like. A generally U-shaped reinforcing rod 22 is secured to the legs by bracing the edges of the end panels about the upright portions of the U-shaped member as shown at 23, and the lower edge 24 of the narrow side wall panel is similarly bent around the cross portion of the U-shaped reinforcing leg, the leg being securely held in place by spot welding or the like.

Rubber feet 25 are secured at the ends of each end panel, as shown in Figure 2, by means of the small metal straps 26, which members are spot welded to the end panels. The wooden top 27 is secured to the top panel 18 by means of wood screws 28.

The legs of the step preferably flare outwardly at the bottom, as shown in the drawings, to such an extent that the edges of the wooden top 27 lie above or within the area outlined by the legs.

A hinge plate 29 is spot welded, or otherwise secured, to the inner surface of the narrow side panel 20, and the strap-like portions 30—30, formed as extensions of the lower edge of this plate, are turned or bent upwardly, as best shown in Figures 2 and 3, to provide a pair of clips to receive the cross portion 31 of a generally U-shaped guide member 32 formed of iron rod or the like. The upright portions of this U-shaped guide member 32 provide the mounting arms 11 and 12.

The hinge plate 29 is so formed that the outermost ends of the strap portions 30 flare outwardly to permit the ready removal of the step from, and re-attachment of the step to, the guide member 32.

It should be noted also that the arms 11 and 12 bear against the under side of the reinforced side wall 20 of the step when the step is in its lowered position, as in Figure 2. This adds a further preventative against tipping of the stool, and particularly against tipping in a direction toward the lavatory or wall.

The inner ends of the arms 11 and 12 are bent laterally to provide the bearing portions 33, best shown in Figure 5, for pivotally or hingedly supporting the arms in the wall brackets 13 or 14. The wall bracket 13 comprises a casing 34, formed of sheet metal, generally U-shaped in horizontal section with laterally extending, mounting flanges 35 and 36, these flanges being provided with openings 37 for the reception of wood screws or the like used to secure the bracket to the wall board 15. The casing 34 is provided, near its upper and forward portion, with a slot 38, in each wall, extending generally forwardly and downwardly, and the transverse portion 33 of the arm 11 is received and is freely rotatable in the lower and forward ends of these slots. A cap 39, having the downwardly extending side walls 40, is provided to cover the open top of the casing 34. The side walls 40 of this cap extend forward to the position indicated by the numeral 41, and it may now be understood that, when the cap is placed in position, the forward edges 41 of the side walls serve to retain the bearing portion 33 of the arm 11 in its proper position in the slots 38. The cap 39 is held in place on the casing by means of the projections 42 on the lower edge of each side wall 40, these projections adapted to engage within the aligned openings 43 in the side walls of the casing.

The toggle arm 44 is affixed to the transverse portion 33 of the arm 11 by welding as indicated at 45. The outer end of this toggle arm is provided with a pin or rivet 46, to which one end of the torsion toggle-spring 47 is pivotally secured. The other end or arm 48 of this toggle-spring is anchored by means of the pin 49 to the side wall of the casing 34. This anchor pin is so positioned that the spring and toggle arm 44 will be on one side of the dead center position when the step is in its lowered or normal position, and will be on the other side of the dead center position or as indicated by dashed lines at 41A and 44A, when the step is in its raised or out-of-the-way position.

A quarter-round section 50 is removed from the lower rear portion of the casing to permit the casing to be installed over a quarter-round molding, such as that indicated at 15A in Figures 1 and 2.

The manner of use of my utility step is believed to be self-evident. When the step is in position for normal use, as in Figure 1, the mounting arms 11 and 12 are urged downwardly by means of the toggle-springs 47 and the step is thus held securely in place against the floor. This arrangement, particularly in conjunction with the outwardly flared legs of the step, practically eliminates the possibility of the step being tipped over. The step may be easily and correctly positioned for use by even a small child and yet may be easily moved back to its out-of-the-way position by simply placing the toe of the

shoe beneath the forward edge and then lifting.

The modified form of wall mounting bracket, as shown in Figure 6, is of somewhat simpler construction than that illustrated in Figures 4 and 5. This bracket comprises a plate-like member 51 having laterally projecting flanges 52 and 53, by means of which, the bracket may be screwed to the wall and floor. The lower rear corner is cut out to permit the bracket to be installed over the quarter-round molding of a base board.

This form of mounting bracket is preferably in the shape of a quadrant, with the curved outer edge 54 flanged and serrated or scalloped as at 55 in order to engage the mounting arm 11B. This mounting arm 11B is similar to the arm 11 described in connection with Figure 1 except that the transverse bearing portion 33A is received through an opening 56 at the center of the quadrant and the outer end of this transverse portion is threaded to receive a nut 57. A leaf spring 58, formed as shown and apertured for reception over the threaded portion 33A, serves to hold the arm 11B in firm engagement with the scalloped flange 54 and thus, when correctly adjusted, will easily support a step in its elevated position in the same manner as the device of Figure 1.

Although I have described specific embodiments of my invention, it is apparent that modifications thereof may be made by those skilled in the art. Such modifications may be made without departing from the spirit and scope of my invention as set forth in the appended claims.

What I claim is:

1. In a device of the character described, a step, a pair of wall brackets adapted to be mounted on a base board, a U-shaped arm hingedly connected, at its ends, to the said wall brackets, and the legs thereof extending between the legs of the step, and a hinge plate mounted on the under-side of the step spaced from the edge thereof, and formed to provide a clip for hingedly and removably engaging the cross portion of the U-shaped arm, whereby the legs of the U-shaped arm will contact the under-side of the step, when the step is lowered, to thereby prevent tipping of the step rearwardly toward the baseboard.

2. In a device of the character described, a step, one or more arms hingedly connected, at one end, to the said step and having transverse bearing portions at their other ends, a wall bracket including a casing having slots in the upper portion thereof for receiving the transverse bearing portion of the arm, a cap adapted to close the top of the casing and secure the bearing portion of the arm within the slots, the arm having an extension thereof disposed within the casing, and a toggle-spring operatively connected to the said extension to selectively urge the arm and the step toward a lowered or a raised position.

3. In a device of the character described for use in conjunction with a lavatory having drain piping extending therebelow, a pair of wall brackets adapted to be mounted below the lavatory and on either side of the drain piping, a U-shaped arm pivotally mounted, at its ends, in the brackets, a step having spaced-apart legs, a hinge plate secured to said step adjacent the underside and between the legs thereof, said hinge plate having clips adapted to detachably engage the cross portion of the U-shaped arm, the said brackets having means for selectively

securing the U-shaped arm in a generally horizontal position or a generally vertical position to thereby selectively secure the stool in lowered position or raised position beneath the lavatory, the step adapted to pivot on the cross bar of the U-shaped arm so as to hang downwardly therefrom with the legs of the step on opposite sides of the drain piping when in raised position.

4. In a device of the character described, including a pair of wall brackets adapted to be mounted on a base board; a step, a U-shaped arm hingedly connected, at its ends, to the wall brackets, means for demountably securing the step to the U-shaped arm comprising a hinge plate mounted on the underside of the step between the legs thereof and formed to provide a hook adapted to pivotally receive the bight of the arm, the hook being so positioned and spaced from the edge of the step that the legs of the

U-shaped arm will contact a portion of the underside of the step, when the step is lowered, to thereby prevent tipping of the step rearwardly toward the brackets.
